US0D1076079S

(12) **United States Design Patent** (10) **Patent No.:** **US D1,076,079 S**
(45) **Date of Patent:** **** May 20, 2025**

(54) **APPLICATOR ASSEMBLY**

(71) Applicant: **INFORMED DATA SYSTEMS INC.**,
New York, NY (US)

(72) Inventors: **Matthew Chapman**, Oakland, CA
(US); **Steven Portela**, San Francisco,
CA (US); **Ashwin Pushpala**, San
Francisco, CA (US); **Mark Prommel**,
Montclair, NJ (US); **Pil Ho Chung**,
Palisades Park, NJ (US)

(73) Assignee: **One Health Biosensing Inc.**, New
York, NY (US)

(**) Term: **15 Years**

(21) Appl. No.: **29/779,913**

(22) Filed: **Apr. 21, 2021**

(51) LOC (15) Cl. **24-02**

(52) U.S. Cl.

CLAIM

The ornamental design for an applicator assembly, as shown and described.

DESCRIPTION

FIG. 1 is a top perspective view of an applicator assembly showing the new design.

FIG. 2 is a left side view of the applicator assembly in FIG. 1.

FIG. 3 is a right side view of the applicator assembly in FIG. 1.

FIG. 4 is a back view of the applicator assembly in FIG. 1.

FIG. 5 is a front view of the applicator assembly in FIG. 1.

FIG. 6 is a top view of the applicator assembly in FIG. 1.

FIG. 7 is a bottom view of the applicator assembly in FIG. 1; and,

FIG. 8 is a bottom perspective view of the applicator assembly in FIG. 1.

The details shown in broken lines illustrate portions of the applicator assembly that form no part of the claimed design. The dash-dot-dash broken lines illustrate the boundaries of the applicator assembly and form no part of the claimed design.
